UNITED STATES PATENT OFFICE.

REID J. McCREDIE, OF BUFFALO, NEW YORK.

LOCK COLLAR-BUTTON.

1,327,719.

Specification of Letters Patent. Patented Jan. 13, 1920.

Application filed November 22, 1918. Serial No. 263,712.

To all whom it may concern:

Be it known that I, REID J. McCREDIE, a citizen of the United States, residing at Buffalo, in the county of Erie and State of New York, have invented a certain new and useful Improvement in Lock Collar-Buttons, of which the following is a specification.

This invention relates to an improved collar button and the principal object of the invention is to provide a collar button so constructed that it may be put in place in the buttonhole of a collar band and locked therein thus preventing danger of the button working loose or becoming lost.

Another object of the invention is to so construct this collar button that it may be easily put in place and locked.

Another object of the invention is to so construct this collar button that the head thereof will be retained in an adjusted position thus permitting the head to be easily passed through the buttonhole of a collar and then turned to a position retaining the collar upon the button.

Another object of the invention is to provide a collar button which will be simple in construction, efficient in operation and which may be placed upon the market at a minimum cost.

This invention is illustrated in the accompanying drawings, wherein:

Figure 1 is a perspective view of the improved button,

Fig. 2 is a sectional view of the button,

Fig. 3 is a view partially in section and partially in elevation of the element which passes through the buttonhole of the collar band.

This collar button is provided with a main section and an anchoring section, the anchoring section having a base 6' from which extends a corrugated tongue 6 for passing through the buttonhole of the collar band.

This tongue has been corrugated so that the main button section may be securely locked upon the tongue as will be hereinafter brought out and the collar band clamped between the base of the anchoring section and

the base of the collar engaging section or main button and thus the button held in place. This main button or collar engaging section is provided with a standard 7 extending upwardly from a base 7' at one edge of a slot 13 and this standard 7 is provided with side flanges 5 thus providing

guides for engaging the tongue 6 and retaining the tongue in proper relation to the standard. It should be noted that this standard is corrugated but to a less extent than the tongue 6 as clearly shown in Fig. 2 thereby permitting a firm interlocking engagement between the tongue and standard when the button is locked upon the anchoring element. A bracket 4 is fastened upon the base 7' and has its bearing arms provided with openings forming sockets to receive the pivot pins 3 of the locking lever 1. This locking lever 1 is positioned as shown in Fig. 2 with its inner end portion bent to provide a spring head 2 which will engage the corrugated tongue 6 and force this tongue into locking engagement with the corrugated standards 7 when the lever is swung to the locking position. The resiliency of this spring head will give the proper binding action to prevent the locking lever from working loose and releasing the collar button. A head 12 is provided for this button and is provided with bearing lugs 9 which are positioned upon opposite sides of the spring tongue 10 and are adapted to receive the pivot pins 8 carried by the tongue of the standard 7. By providing a slot 11 in the standard the resiliency of the latter is increased thereby maintaining the head 12 in adjusted position, thus permitting the head 12 to be easily swung to extend either parallel to the standard or at right angles to the same thus permitting the head to be passed through the buttonhole of a collar and then turned to retain the collar in place upon the button.

In the operation the anchoring member will be placed in the buttonhole of the collar band and the button or collar engaging element will then be put in place with the tongue 6 extended through the slot 13 and into engagement with the standard and flanges 5 of the standard. The locking lever will now be swung to the locking position and will engage the tongue to move the tongue into tight engagement with the corrugated standard and retain the collar engaging member in tight engagement with the tongue. The collar band will now be firmly secured between the base 6' of the anchoring member and the base 7' of the collar engaging member and there will be no danger of the collar button working loose and becoming lost. The head will be turned to extend substantially parallel to the stand-

ard and the head and standard can then be easily passed through the buttonhole of the collar. After the collar is in place the head will be turned to extend at rightangles to the standard and the collar will be retained in place. It will thus be seen that there has been provided a collar button in which the collar engaging member can be securely locked in place and further that there has been provided a collar button in which the locking and releasing of the collar engaging member will be easy to accomplish.

What is claimed is:

1. A collar button comprising a collar engaging section having a base provided with a slot, a standard extending from the base to one side of the slot and provided with side flanges positioned about the end portions of the slot, a bracket carried by the base, a locking lever pivotally connected with the bracket having its inner end portion provided with a resilient head, and an anchoring element having a base and a tongue extending through the slot formed in the base of the collar engaging element and into engagement with the standard and flanges, the locking lever when swung to a locking position engaging the tongue to clamp the same in engagement with the standard.

2. A collar button comprising a collar engaging element and an anchoring element, the collar engaging element having a base provided with a slot, a standard extending from the base and transversely corrugated, a locking lever pivotally connected with the base adjacent the standard, the anchoring element having a base and a tongue extending from the base to the slot of the base of said collar engaging element and transversely corrugated, the locking lever when swung to an operative position engaging the corrugated tongue to hold the same in interlocking engagement with the corrugated standard.

3. A collar button comprising a collar engaging element and an anchoring element, the collar engaging element having a base provided with a slot and a standard extending from the base adjacent the slot, the anchoring element having a base and a tongue extending from the base and adapted to pass through the buttonhole of a collar band and through the slot of the base of said collar engaging element, said tongue and standard having corrugations and means carried by flanges, the locking lever when swung to a locking position engaging the tongue to hold the tongue and standard corrugations in engagement with the standard.

REID J. McCREDIE.
